ABSTRACT

A pack frame having side frame members and cross-bars extending between the side frame, worn on the back by means of a pair of shoulder straps with the lower ends of the side frame members pin-connected to a hip belt for transferring part of the load carried by the frame to the wearer's hips. In another aspect, the side frame members have wheels at their lower ends and connecting members at their upper ends for attachment to the hip belt for rolling the frame over the ground, the user pulling it forward as he walks via the attachment of the frame to the hip belt. The connecting members are movable between a retracted position extending toward one another from the opposite sides of the frame for utilization of the frame as a back pack frame, and a position extending forward for utilization of the frame as a rolling cart.

PACK FRAME

BACKGROUND OF THE INVENTION

This invention relates to pack frames, and more particularly to pack frames with a hip belt for supporting part of the load on the user's hips. It also involves a wheeled frame adapted to be attached to the hip belt and rolled over the ground.

Reference may be made to such U.S. patents as 3,367,547, 3,516,586 and 3,581,961 showing conventional pack frames having their lower ends connected to a hip belt.

SUMMARY OF THE INVENTION

Among the several objects of this invention may be noted the provision of a pack frame such as above described having improved more comfortable means for connection thereof to a belt worn around the hips of the user; the provision of such pack frame with such means enabling easy adjustment for fitting different users; the provision of such a pack frame with wheels and means for attaching it to the belt for being pulled forward by the user as he walks forward; and the provision of such a wheeled pack frame which is equally alternatively useful as a frame to be worn on the back.

In general, a pack frame of this invention comprises a pair of generally parallel, spaced-apart side members, a plurality of cross members extending between the side members and secured thereto, a pair of shoulder straps each having one end thereof secured to the upper portion of the pack frame and having its other end secured to the lower portion of the pack frame, and a hip belt having pad means engageable on the wearer's hips and a strap secured to the outer surface of the pad means adapted to encircle the wearer. The strap has means on its ends for fastening the hip belt in place around the hips, and means at each side for connecting the lower portion of a respective side member to the hip belt for transferring a portion of the weight of the load carried by the pack frame to the wearer's hips. This connection means comprises at least one hole in the strap at each side of the hip belt adjacent the lower end of a respective side member, a hole in the lower portion of each side member, and a removable fastening member extending through the hole in the strap and through the hole in the adjacent side member for connecting the lower portion of the side member to the hip belt with the pad means interposed for comfort between the fastening member and the wearer's body. Other objects and features will be in part apparent and in part pointed out hereinafter.

BRIEF DESCRIPTION OF THE DRAWINGS

FIG. 1 is a side elevation of a wheeled pack frame of this invention as it is worn on the back;

FIG. 2 is a side elevation of the FIG. 1 pack frame as it is connected by connecting members to a hip belt worn around the hips with the pack frame rolling along the ground behind the wearer on its wheels;

FIG. 3 is a view on line 3-3 of FIG. 1 showing the connecting members in retracted position enabling the pack frame to be worn on the back;

FIG. 4 is a rear elevation on line 4-4 of FIG. 2 showing the wheeled pack frame as it is connected to the hip belt for rolling along behind the wearer;

FIG. 5 is an enlarged vertical section on line 5-5 of FIG. 1 showing the connection of the lower portion of the pack frame to the hip belt when the pack frame is worn on the back;

FIG. 6 is an enlarged vertical section on line 6-6 of FIG. 2 showing the connection of the connecting members to the hip belt;

FIG. 7 is an enlarged detail on line 7-7 of FIG. 4, with parts broken away;

FIG. 8 is an enlarged vertical section on line 8-8 of FIG. 1;

FIG. 9 is a side elevation similar to FIG. 1 showing a non-wheeled modification for being worn on the back only; and

FIG. 10 is a rear elevation of the FIG. 9 frame.

Corresponding reference characters indicate corresponding parts throughout the several views of the drawings.

DESCRIPTION OF THE PREFERRED EMBODIMENT

Referring to the drawings, a pack frame of this invention, indicated in its entirety at 1, is shown to comprise a pair of generally parallel, spaced-apart side frame members 3a and 3b, and a plurality of cross members each designated 5. A pair of shoulder straps is provided for suspending the frame from the shoulders on the user's back. Each of these straps is designated 7 and has its upper end detachably connected to the top cross member 5 as indicated at 9 and its lower end detachably connected to the lower end portion of a respective side member 3a or 3b, as indicated at 11. The cross members 5 are constituted by curved bars extending between the side members (also constituted by bars). Support rods 13 extend vertically of the pack frame between cross members 5 for supporting the load carried in a suitable pack 15 (shown in phantom in FIG. 1) secured to the pack frame. A resilient web 16 (e.g., an open mesh fabric web) extends transversely of side members 3a, 3b intermediate their ends and is adapted to bear against the wearer's shoulder blades to support the pack frame against his back. A hip belt generally indicated at 17 is worn around the wearer's hips for purposes that will appear.

As shown in FIGS. 1, 2 and 4 the pack frame 1 has a pair of wheels 19a, 19b, each rotatably carried on a stub axle 20a, 20b secured to the lower end of a respective side member 3a, 3b. The frame also has a pair of connecting members 21a, 21b carried by the upper ends of the side members 3a and 3b, respectively, adapted to be pivotally connected to the hip belt assembly to hold the pack frame in position for rolling along the ground on the wheels behind the wearer as the wearer walks forward (see FIG. 2). Alternatively, the pack frame may be worn on the back (as shown in FIG. 1) supported by shoulder straps 7 and also by connection of the lower portions of side members 3a, 3b to the hip belt thereby to transfer a portion of the weight of the load carried by the pack frame to the wearer's hips and thus relieve strain on the shoulders. Wheels 19a, 19b are located on the outside of the lower portions of the side members 3a, 3b spaced apart a distance greater than normal hip width. The connecting members 21a, 21b are movable from their extended connecting positions (FIG. 2) in which they extend forward from the side members for connection to the hip belt to a retracted position (see FIGS. 1 and 3) in which

each connecting member extends inwardly crosswise of the frame toward an opposite side member clear of the wearer. Thus, the pack frame of this invention may be trailed behind the user on the wheels 19a, 19b with the wheels supporting the load carried by the pack frame, or may be worn on the back as a conventional pack frame without interference from the wheels or the connecting members.

As shown in FIGS. 5-7, the hip belt 17 comprises a pad generally indicated at 23 engageable on the wearer's hips and a strap 25 secured to the outer surface of the pad adapted to encircle the wearer. Pad 23 includes an elongated piece of flexible, resilient foam material 27, such as polyurethane foam, of sufficient length partially to encircle the wearer from one hip across the small of the back to the other hip. A protector member 29 of relatively thin, stiff material, such as a suitable plastic, is bonded as by a suitable adhesive to the outer surface of the foam, as indicated at 31, at each side of the hip belt assembly, and a fabric cover 33 of nylon fabric or the like encloses the foam 27 and the two protector members 29. Strap 25 has buckle members on its ends as indicated at 35 for fastening the hip belt on the wearer. The strap is stitched to the outer surface of the cover 33 along lines 36a and 36b at the longitudinal margins of the strap, but with the strap free in part, as indicated at 37; from the cover along its lower margin at the sides of the hip belt via gaps in the stitching 36b.

The forward ends of connecting members 21a, 21b are pivotally connected to the hip belt when the pack frame is trailed behind the wearer, and the lower ends of the side members 3a, 3b are pivotally connected to the sides of the hip belt when the pack frame is worn on the back, by means generally indicated at 38. More particularly, this means includes a series of holes 39 in strap 25 at each side of the hip belt, two such holes being shown at each side of the hip belt enabling adjustment of the connections to suit the user. Each of these holes is reinforced by a grommet 41. As shown best in FIG. 5, a hole 43 is provided in the lower end portion of each side member 3a, 3b, and as shown in FIG. 7 a plurality of holes 45 is provided in the forward portion portion of each connecting member 21a, 21b. A removable pin 47 having a head 49 is insertable through one of the holes 39 in strap 25 at each side of the hip belt from the side of the strap toward pad 23 and through the hole 43 in the lower end of the adjacent side member, or through a hole 45 in the front end portion of an adjacent connecting member 21a or 21b thereby pivotally to connect the side members or the connecting members (as the case may be) to the hip belt. With the connecting members attached to and pivoted on pins 47, the pack frame may swing relative to the wearer about the axis of the pins for accommodation to ground contour. Each pin 47 has a diametric hole at its outer end for receiving a wire keeper ring 53 to keep the pin in its hole 43 or 45, this ring being a conventional split ring.

The holes 39 are provided in the strap 25 where it is free in part of the cover 33 at 37 along its bottom margin. This enables the strap to be separated from cover 3 to permit pin 47 to be inserted through hole 39. With the pin inserted through the hole as shown in FIGS. 5 and 6, the head 49 of the pin bears against the outside of the cover 33 for pad 23 of the belt and against the protector member 29 bonded to the foam material 27

within the cover to prevent the head of the pin from pushing against and gouging the pad and the wearer, thus avoiding discomfort to the wearer.

Side members 3a, 3b may conveniently be formed of metal tubing of circular cross-section, the bore thereof being designated 55. The lower end of each side member is bent slightly to the rear, as indicated at 57, for mounting wheels 19a, 19b with their axes slightly to the rear of the plane of the pack frame. Connecting members 21a, 21b may also be of metal tubing of circular cross-section and each is bent as indicated at 59 to have an arm portion 61 extending at an angle of about 110° from the upper end of a leg portion 63. The lower end of the leg 63 of each connecting member (which is of circular cross-section) is rotatably received within the bore 55 of the respective side member 3a, 3b at the upper end of the latter. Thus, each connecting member is swingable at the upper end of its respective side member between its extended connecting position in which it extends forwardly of its respective side member for being pivotally connected by pin 47 to hip belt 17 and its retracted position.

A diametric hole 65 is provided at the upper end of each side member 3a, 3b for receiving a pin 67 similar to pin 47. The lower end of leg 63 of each of the connecting members 21a, 21b has two diametric holes 69 and 71 therethrough at 90° to one another and located so that with pin 67 extending through hole 65 in the side member and through hole 69 in the connecting member, the latter is pinned in its forwardly extending belt-connecting position, and with the pin extending through holes 69 and 71 the connecting member is pinned in its retracted position.

Thus, with the pack frame 1 pivotally connected to the hip belt 17 as shown in FIG. 2, the frame may be trailed along behind the wearer on wheels 19a, 19b if the terrain is suitable, or the frame may be worn on the back without interference from the wheels or the connecting members 21a, 21b when the terrain does not permit the pack frame to be trailed on the wheels. The construction of the hip belt 17 protects the wearer from being gouged by pins 47 when the pack frame is either trailed behind the wearer on its wheels or worn on the back.

FIGS. 9 and 10 show a modification of the frame 1 without wheels for being carried on the back only. The frame, here designated 1a to distinguish it from the frame 1, is substantially identical to the frame 1 above described, except that it does not have any wheels, and the side frame members, here designated 3c and 3d are formed as the sides of an inverted U-shaped length of tubing generally designated 81, the top bar of the latter being designated 83. Three crossbars 5, corresponding to bars 5 of the frame 1, span the side frame members 3c and 3d. The latter are somewhat shorter than side frame members 3a and 3b, otherwise the frame 1a is the same as the frame 1, and it is used with the same hip belt 17.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

What is claimed is:

1. A pack frame comprising a pair of generally parallel, spaced-apart side frame members and cross members extending between the side members, a pair of shoulder straps for the pack frame and a hip belt comprising pad means engageable on the wearer's hips, a strap secured to the outside of the pad means adapted to encircle the wearer, means at the ends of the strap for fastening the hip belt in place on the wearer, and means for connecting a respective side member adjacent its lower end to the hip belt at each side of the belt as it is worn for transferring a portion of the weight of the load carried by the frame to the wearer's hips, said connecting means comprising at least one hole in the strap at each side of the hip belt, a hole in each side member adjacent its lower end, and a headed pin at each side of the hip belt extending through the respective hole in the strap and the hole in the respective side member for connecting each side member adjacent its lower end to the hip belt, said strap being free in part of the pad means to permit the pin to be inserted through the hole in the strap from the side thereof toward the pad means and through the hole in the adjacent side member, with the head of the pin bearing against the outside of the pad means, said pad means including a relatively thin, stiff protector member between the head of each pin and the pad means, a body of resilient, flexible foam material of such length as to extend around the wearer's back from one side to the other, and a cover enclosing the foam material, said protector member being bonded to the outside of the foam and being enclosed within the cover, and said strap being stitched to the outside of the cover, so that the pad means including said protector member, when worn by the wearer, is interposed as a cushion between said headed fastener member and the wearer and said protector member prevents gouging of the wearer by said headed fastener member.

2. A pack frame as set forth in claim 1 wherein said

strap has a series of holes therein at each side of the hip belt providing different horizontal positions along the belt for the pins.

3. A pack frame as set forth in claim 1 wherein the strap is free of the cover along the regions of the series of holes via gaps in the stitching of the strap to the cover for insertion of the pins.

4. A pack frame comprising a pair of generally parallel, spaced-apart side frame members and cross members extending between the side members, a pair of shoulder straps for the pack frame and a hip belt comprising pad means engageable on the wearer's hips, a strap secured to the outside of the pad means adapted to encircle the wearer, means at the ends of the strap for fastening the hip belt in place on the wearer, and means for connecting a respective side member adjacent its lower end to the hip belt at each side of the belt as it is worn for transferring a portion of the weight of the load carried by the frame to the wearer's hips, said connecting means comprising at least one hole in the strap at each side of the hip belt, a hole in each side member adjacent its lower end, and a headed pin at each side of the hip belt extending through the respective hole in the strap and the hole in the respective side member for connecting each side member adjacent its lower end to the hip belt, said pad means including a body of resilient, flexible foam material of such length as to extend around the wearer's back from one side of the wearer to the other and a cover enclosing the foam material, said strap being stitched to the outside of the cover, said holes in the strap overlying the outside of said cover at the sides of the hip belt, and said strap being free of the cover at each side of the hip belt adjacent said holes therein via gaps in the stitching of the strap to the outside of the cover to permit said headed pin to be inserted through the hole in the strap from the side thereof toward the pad means and through the hole in the adjacent side member.
